UNITED STATES PATENT OFFICE.

ALBERT SCHWARZ, OF CHICAGO, ILLINOIS, ASSIGNOR OF ONE-TENTH TO FRANCIS A. DOYLE, OF CHICAGO, ILLINOIS.

BULLET-PROOF SHIELD.

1,203,916.

Specification of Letters Patent.

Patented Nov. 7, 1916.

Application filed July 8, 1916. Serial No. 108,120.

To all whom it may concern:

Be it known that I, ALBERT SCHWARZ, a subject of the Emperor of Austria-Hungary, who have declared my intention of becoming a citizen of the United States, residing at Chicago, in the county of Cook and State of Illinois, have invented a new and useful Improvement in Bullet Proof Shields, of which the following is a specification.

My invention relates to bullet-proof shields or jackets, and has for its object the provision of simple and efficient means for stopping and holding bullets fired from revolvers, rifles, and the like.

A further object is the provision of a device of this character which is of minimum weight, and easily and quickly taken on and put off by a wearer.

Other objects will appear hereinafter.

An embodiment of my invention is shown in the accompanying drawings, forming a part of this specification, and in which—

Figure 1 is a front view of a shield embodying my invention with portions torn away to expose underlying parts. Fig. 2 is an enlarged fragmental section taken on a vertical line near the center of the shield. Fig. 3 is an enlarged fragmental portion shown in perspective; and, Fig. 4 is a view showing two of the shields of Fig. 1 attached together for use.

My invention is adapted to be worn by soldiers, and others who are likely to come in the range of rifle and revolver shooting. It is adapted to catch a bullet from a rifle or revolver, stop the same, and prevent its rebounding or glancing.

My device consists essentially of a plurality of hard stiff layers of material spaced apart by comparatively thick quilted or soft material, so that when a bullet pierces one of the hard layers, the impact of the bullet will not be transmitted directly to the next hard member, but part of the shock of the bullet will be taken up by the soft material before it engages the next hard layer. In this manner, I find that a few comparatively thin layers of hard steel spaced apart by cloth fabric will effectively stop the most powerful rifle bullets now in use. In use,

I preferably use highly tempered Swedish steel, which is blued, and silk cloth between the Swedish steel sheets. Other kinds of steel or cloth may be used, when so desired, without departing from my invention.

Referring more particularly to the drawings, the form I have illustrated, comprises a sack or envelop made up of a front sheet 5, and a rear sheet 6. The front sheet 5 is outermost when the device is in use, and the sheet 6 next to the body of the wearer. The bullet resisting material is placed in the sack or envelop and held therein by stitchings, or in any other suitable manner. The bullet resisting material, as illustrated, comprises first adjacent the sheet 6, a layer made up of one or more thicknesses of woven wire fabric 7, inclosed in a cloth cover 8. In the form shown, two thicknesses of wire fabrics 70 are used. The wire fabric 7 is preferably soft wire, such as is used for fly-screens, but may be of any other suitable or desirable fabric. The next layer of the bullet resisting material is a layer of sheet steel 9, preferably of a single thickness, having a plurality of turns of cloth wrapped around it forming a thick pad on each of its sides. The pad 10 at one side of the sheet 9 is provided with quilting stitches 11, and the pad 12 at the other side of the sheet 9 is provided with stitches 13. The stitches 11 and 13 give the pads firmness and facilitate holding them in place. The sheet steel 9 is shown as being made up of two pieces but it may be divided into as many pieces as desired. When the sheet steel 9 is divided into more than one piece, each piece is placed in an envelop 14 and the envelops secured together by stitchings to hold them in place.

The cracks between the pieces of sheet 9 are covered by strips 15 and the latter inclosed in envelops 16 to provide an easy means for securing the strips in position over the cracks. The next layer of the bullet resisting material comprises an envelop or covering of cloth 17 inclosing a single thickness of wire fabric 18, similar to the wire fabrics 7, and a thickness of padding 19 of cotton batting, felt, or the like. The wire fabric 18 and padding 19 are held in proper position in the envelop 17 by means of quilting

stitches 20. On the last mentioned layer is disposed a layer made up of a plurality of turns of cloth 21 wound around a steel member. The steel member is made up of thin strips of spring steel woven together so that the woof strands touch each other in order to prevent forming openings between the woof and warp strands of the fabric (see Fig. 3). The steel member 22, like sheet 10 steel 9, may be made in a single member reaching through the whole shield or, as shown, made up of a plurality of narrow parts disposed in edge to edge relations, and each of such parts having its covering 21 wrapped only around itself. The strips 22 are preferably thin spring steel having a maximum amount of resiliency and strength.

The topmost layer of the bullet resisting material, as illustrated, is made up of a 20 plurality of plates 23 of sheet metal disposed in overlapping relations and each plate wrapped in a plurality of turns of cloth 24 forming pads on the sides of the plates. The steel plates 23 and 9 are preferably considerably thicker and more rigid than the metal in strips 22. It is not essential that the plates 23 be placed in overlapping relations but may be placed in the relations of the parts 9 with strips 30 lapping the adjacent edges thereof.

When a bullet is fired into a shield of this kind, it penetrates one or more of the layers according to the force exerted upon the bullet. In use a 45-caliber bullet fired from 35 an army revolver or pistol penetrates to a depth such as indicated in Fig. 2, as at 25. Bullets of the sharp nose type fired from the high power rifles now in use penetrate to the sheet steel 9 or even fracture the latter 40 but do not have sufficient force to reach through the entire shield. The number of layers having the steel sheet centers may be varied as desired but each one must be provided with its separate pad to give it 45 its maximum bullet resisting power.

As a bullet enters the shield it becomes flattened, see Fig. 2, and carries with it parts of the layers of the shield until it gets so large that its energy is all absorbed 50 and it stops. The soft materials prevent the bullet from rebounding or glancing out of the shield. The soft materials under the woven strips 22 permit the latter to yield under the influence of a bullet, thereby 55 greatly increasing their resisting power.

I claim:

1. A bullet-proof shield comprising a plurality of layers of hard sheet metal; layers of metal wire fabric; and layers of cloth 60 fabric between and spacing the layers of sheet metal and layers of wire fabric apart.

2. A bullet-proof shield comprising highly tempered sheet metal plates, and a plurality of thicknesses of silk fabric between said 65 metal plates.

3. A bullet-proof shield comprising a plurality of layers of metallic material, certain of said layers being hard sheet metal plates and other of said layers being metal woven wire; and layers of tough material between 70 said other layers of material.

4. A bullet-proof shield comprising a plurality of layers of metallic material, certain of said layers being hard imperforate plates, other of said layers being woven 75 from strips of hard metal and still other of said layers being woven wire fabric; and layers of cloth material between the metallic layers.

5. A bullet-proof shield comprising a 80 layer of woven wire fabric; a layer of highly tempered steel sheets above the woven wire fabric; a layer of fabric woven of strips of highly tempered steel above said steel sheets; a layer of highly tempered 85 steel above said last mentioned fabric; and thick layers of cloth material separating said metallic layers.

6. A bullet-proof shield comprising a 90 layer of woven wire fabric; a layer of highly tempered steel sheets above the woven wire fabric; a layer of wire fabric above said steel sheets; a layer of fabric woven from strips of highly tempered steel above said last mentioned wire fabric; a 95 layer of highly tempered steel plates above the fabric woven of said steel strips; and layers of soft tough material between and separating said metallic layers.

7. A bullet-proof shield comprising a 100 layer of stiff hard steel; a layer of cloth material under the steel layer; a layer of material made up of strips of spring steel under said cloth layer; a layer made up of flexible fabric and wadding material under 105 the layer of spring steel strips; and a layer of hard stiff steel under the layer of flexible fabric and wadding material.

8. A bullet-proof shield comprising a plurality of layers of sheet steel members; a 110 plurality of thicknesses of cloth fabrics between and separating the layers of steel; a layer of soft yielding wadding under certain of the layers of steel members; and a layer of wire cloth secured to one side of the wadding.

9. A bullet-proof shield comprising a layer of woven wire fabric; a cloth covering on said wire fabric; a pad of quilted cloth on said covering; a layer of hard stiff steel 120 sheets on said pad; a quilted cloth pad on said steel sheets; a woven wire fabric on said last mentioned quilted cloth pad; a layer of cotton wadding on said last mentioned woven wire fabric; a pad of cloth 125 on said wadding; a layer of material made up of strips of spring steel woven together on said last mentioned cloth pad; a cloth pad on said layer of spring steel strips; a layer of steel sheets on said last mentioned 130

cloth pad; a cloth pad on said last mentioned steel sheets; and an envelop inclosing all of the aforesaid parts.

10. A bullet-proof shield comprising a plurality of layers of metal, certain of said layers being imperforate metal plates and other of said layers being woven of thin

flat strips of metal; and layers of tough cloth fabric between the layers of metal.

In testimony whereof I have signed my name to this specification on this 28th day of June A. D. 1916.

ALBERT SCHWARZ.
